UNITED STATES PATENT OFFICE.

ADOLPH E. BINDER, OF SPOKANE, WASHINGTON.

GRATE BAR AND SUPPORT.

Application filed December 11, 1925, Serial No. 74,806. Renewed May 31, 1927.

This invention relates to new and useful improvements in grates, and particularly to furnace grates.

One object of the invention is to provide a support for a grate bar section which will effectively maintain the grate bar section against movement longitudinally or transversely of the support.

Another object is to provide a support for a grate bar section which permits free circulation of air between it and the grate bar support, for the purpose of preventing the section from burning out too rapidly, and also for maintaining the support in a cool condition.

A further object is to provide a grate bar section made up of a number of parts, thus permitting the replacing of a burned out part, without the necessity of removing the entire grate, or the entire grate bar.

A further object is to provide a novel means for suspending the grate bar support on the walls of the ashpit, whereby a comparatively rigid structure is produced.

Other objects and advantages will be apparent from the following description when taken in connection with the accompanying drawing.

In the drawing:

Figure 1 is a top plan view of a grate bar made in accordance with the present invention.

Figure 2 is a vertical longitudinal central sectional view on the line 2—2 of Figure 1.

Figure 3 is a side elevation of the device.

Figure 4 is a vertical transverse sectional view on the line 4—4 of Figure 1.

Figure 5 is an end view of the support.

Figure 6 is a perspective view of the hanger.

Referring particularly to the accompanying drawings, 10 represents the side walls of the ashpit of a furnace, in connection with which the invention is used, said walls having the inwardly directed lugs 11, on which the support is arranged to be suspended. The support comprises the longitudinal side bars 12 which are deepest at the center, and gradually reduced toward the opposite ends.

Connecting the bars 12, adjacent the ends thereof, and intermediate said ends, are the transversely extending bars 13, the upper faces of which are transversely and oppositely beveled, as shown at 14. Connecting the ends of the bars 12, outwardly of the bars 13, are the transverse webs 15, each of

which is formed with a downwardly opening notch 16 in its lower edge. The upper edge portion of each of the bars 12, throughout the entire length thereof, is downwardly and inwardly beveled, as shown at 17, and is formed with a longitudinal series of upwardly extending, and regularly spaced lugs 18.

Disposed on the upper faces of the lugs 18, of the support, is the upper portion of the grate bar, said portion including separable sections 19 each of which comprises a casting having transverse oblique bars 20 resulting in intervening oblique slots 21, and the longitudinal connecting side bars 22. Formed on the lower faces of certain of the bars 20 are the depending lugs or webs 23, which engage between the side bars or walls 12, of the support, and have their ends beveled to rest on the beveled faces 17 of the side bars or walls, whereby said sections are held against lateral movement on the support. The ends of the side bars 22, of each section 19, project short distances beyond the end bars 20 for abutting engagement with corresponding portions of the bars of the adjacent sections, whereby to properly space the end bars 20 to provide for intervening slots, between the sections.

Resting on the lugs 11, of the ashpit walls 10, are the horizontal wings of the angle plates 25, and formed on the exposed face of the depending vertical wing of each plate is a substantially T-shaped lug 26, which is arranged to engage in a slot or notch 16, of an adjacent web 15 of the support. The inner face of the head portion of the lug 26 is inclined to provide for a wedging action with the inner face of the web, whereby to firmly retain the support in place, and prevent any tendency toward looseness. This construction also permits easy and quick removal or replacement of the support.

The beveled faces of the bars of the support serve to direct the ashes which fall between the bars of the grate bar sections, down into the ashpit.

The lugs 18 support the sections 19 of the grate bar above the support, while the spaces between the lugs permit the free passage of air between the support and said sections, whereby both the sections and support are maintained in a cool condition, which will prevent too rapid burning out of the grate. Furthermore, the fact that the grate bar is formed of separable sections, permits the

easy removal of a burned out section, thereby obviating the replacing of the entire grate, or grate bar.

What is claimed is:

5 The combination with the walls of an ash-pit having longitudinal ribs thereon, of a grate bar including a pair of L-shaped brackets engaged on said ribs, each of the brackets having a horizontal headed lug projecting from its lower end portion, a support having parallel side bars formed with spaced elevated portions on the upper edges and transverse connecting and spacing bars, the

endmost of the transverse bars having vertical wedge notches receiving said headed 15 lugs, the upper edge portions of the said side bars being beveled inwardly, and transversely barred sections seated on the said elevated portions and having certain of the bars thereof extended downwardly between 20 the parallel bars of the support and the ends thereof beveled in correspondence with and for engaging the beveled portions of the parallel bars of the support.

In testimony whereof, I affix my signature.

ADOLPH E. BINDER.
